UNITED STATES PATENT OFFICE

PAUL E. HEAL, OF MARION, INDIANA

DESIGN FOR A LAWN-SPRINKLER NOZZLE

Application filed November 21, 1929. Serial No. 33,516. Term of patent 3½ years.

To all whom it may concern:

Be it known that I, PAUL E. HEAL, a citizen of the United States, residing in the city of Marion, in the county of Grant and State of Indiana, have invented a new, original, and ornamental Design for a Lawn-Sprinkler Nozzle, of which the following is a specification, reference being had to the accompanying drawing, forming part hereof.

The figure is a perspective view of a lawn sprinkler nozzle, showing my new design.

I claim:

The ornamental design for a lawn sprinkler nozzle as shown.

PAUL E. HEAL.
